(57) **CLAIM**

The ornamental design for a non-contact type data carrier, as shown and described.

DESCRIPTION

The patent or application file contains at least one drawing executed in color. Copies of this patent or patent application publication with color drawing(s) will be provided by the Office upon request and payment of the necessary fee.

FIG. 1 is a rear elevational view of a non-contact type data carrier showing my new design;

FIG. 2 is a right side elevational view thereof;

FIG. 3 is a top plan view thereof; and,

FIG. 4 is a bottom plan view thereof.

The broken lines illustrate unclaimed portions of the non-contact type data carrier and form no part of the claimed design. The dot-dash broken lines defining the boundaries of the claimed design form no part of the claimed design.
